UNITED STATES PATENT OFFICE.

MARTIN L. BIBB, OF SEATTLE, WASHINGTON.

CLEANING DEVICE.

Application filed June 13, 1924. Serial No. 719,844.

To all whom it may concern:

Be it known that I, MARTIN L. BIBB, a citizen of the United States, residing at Seattle, in the county of King and State of Washington, have invented certain new and useful Improvements in Cleaning Devices; and I do hereby declare the following to be a full, clear, and exact description of the invention, such as will enable others skilled in the art to which it appertains to make and use the same.

This invention relates to an improved construction of a cleaning device, and more particularly to a combined cleaning and wiping implement which will efficiently clean windows and like objects without scratching the same or injuring the surrounding border or molding.

An object of the invention is to provide a combined cleaner and wiping device for cleaning windows which will be provided with a removable and renewable chemicalized cleaning pad and a plurality of adjacent wiping strips of rubber, so that the windows to be cleaned may first be gone over with the dampened chemicalized pad and wiped dry with the rubber strips.

A further object of the invention is to provide a combined cleaning and wiping implement for windows which will be highly efficient in use and quite inexpensive to manufacture.

Other objects will appear as the description proceeds.

In the accompanying drawings which form a part of my application:

Fig. 1 is a plan view of my improved window cleaning and wiping implement.

Fig. 2 is a rear elevation of the same, and

Fig. 3 is a transverse sectional view taken on line 3—3 of Fig. 2.

Like characters of reference are used throughout the following specification and the accompanying drawings to designate corresponding parts.

My improved device comprises an elongated body plate 1 which has its rear portion bent downwardly a slight distance at substantially right angles thereto, as at 2, and has its forward portion bent upwardly at a slight angle. A plurality of spaced tabs or tongues 3 are punched from the downwardly extending portion 2 of the body plate and extend inwardly at an angle toward the bottom surface of the said body plate.

The cleaning pad 4 is preferably made from felt or like material and is chemicalized or impregnated with a suitable cleansing fluid, so that when the same is moistened with water the action of the cleansing fluid will thoroughly and efficiently remove any particles of grease or dirt from a window pane. The pad 4 extends a short distance beyond each end of the body plate 1 and is securely fastened to a rigid supporting plate 5 by means of the rivets 6. The rear edge of the plate 5 is bent upwardly so that it will be engaged and firmly supported between the bottom surface of the body plate 1 and the plurality of tongues 3, while the forward edge of the plate 5 is bent downwardly and is adapted to be securely clamped by the bent edge 7 of the clamping strip 8.

The clamping strip 8 extends in spaced relation to the upwardly extending forward portion 9 of the body plate 1, between which a plurality of rubber wiping strips 10 are adapted to be clamped in fixed position by means of the several bolts 11 which extend between said strip 8 and the annular portion 9 of the body plate.

A shank 12 for the handle socket 13 is securely held to the body plate 1 by means of the rivets 14.

From the foregoing description it will be apparent that when it is desired to clean a window it is only necessary to dip the cleaning pad into the bucket of water and run the same over the surface of the window to be cleaned, after which the wiping strips will be drawn across the surface of the window to dry and remove all particles therefrom.

It will further be understood that when a wiping strip has become worn out, a new strip may readily be substituted therefor and likewise when the rubber wiping strips have become worn out new ones may be substituted.

Many minor changes in detail of construction and operation may be resorted to without departure from the spirit of my invention.

What I claim is:

A device of the character described comprising a body plate having a laterally directed flange, spaced tabs extending from said flange inwardly, under the plate, a supporting plate of less width than the body plate having one edge provided with a flange

spaced from the flange of the body plate, a pad secured to the supporting plate between the flanges, a wiper strip and a clamping strip having one edge provided with a flange adjacent flange of the supporting plate and means for adjustably securing the clamping plate to the body plate with the wiper strip interposed the flanges of the clamping strip

and supporting plate interlocking to constitute a pivot for the clamping plate and to secure all the parts in assembled relation as specified.

In testimony whereof I affix my signature.

MARTIN L. BIBB.
